[57] CLAIM

The ornamental design for a dragline bucket, as shown.

DESCRIPTION

FIG. 1 is a plan view;
FIG. 2 is a rear perspective view, but it is viewed from slightly right and above a rear view;
FIG. 3 is a side view, of the left side;
FIG. 4 is a right side perspective view, but it is viewed from slightly below and forward a right side view;
FIG. 5 is a left side view, with a broken line showing a precise tilt back rigging attached to the bucket. This view illustrates the bucket carrying a load of earth. The broken line showing is for illustrative purposes only and forms no part of the claimed design;
FIG. 6 is a front view; and,
FIG. 7 is a rear view.
